UNITED STATES PATENT OFFICE.

WARREN C. REES, OF SOMERVILLE, MASSACHUSETTS, ASSIGNOR TO ASEPTIC SERVICE COMPANY, OF BOSTON, MASSACHUSETTS, A CORPORATION OF MAINE.

WATER-CLOSET SEAT.

1,165,123.

Specification of Letters Patent. Patented Dec. 21, 1915.

Application filed June 19, 1915. Serial No. 35,158.

To all whom it may concern:

Be it known that I, WARREN C. REES, a citizen of the United States, and resident of Somerville, in the county of Middlesex and 5 State of Massachusetts, have invented certain new and useful Improvements in Water-Closet Seats, of which the following is a specification.

The present invention relates to seats for 10 toilets and has for its object generally to provide a seat which can be kept clean and sanitary conveniently and with ease. In further stating this object, it may be observed that it is a common practice to place 15 a covering of paper, or other material, upon seats of this sort, particularly those provided for public use, and that my purpose is to enable such sheets to be disposed of automatically after each use of the toilet and in 20 a neat way.

Another object is to enable the seat to drain directly into the toilet bowl. To that end I arrange the seat and provide means for so operating the same that when not in 25 use the seat is raised and withdrawn from the toilet bowl and held in such a way that the seating surface thereof is turned toward the bowl instead of away therefrom, whereby any covering of paper, etc., or anything 30 else which may have been placed on the seat may be discharged automatically into the bowl.

There are a number of constructions in 35 which my invention may be embodied, and of such I have illustrated two in the accompanying drawings. In one of such illustrated forms the seat is composed of two members arranged adjacent to opposite sides of the toilet bowl, each constituting half of 40 the entire seat, and in the other the entire seat is made as a unit located at the back of the toilet when not in use.

Figure 1 is a perspective view of the toilet 45 having the two part seat embodying this invention. Fig. 2 is a front to rear section of the casing which contains the operating mechanism for one of the parts of the seat, showing the adjacent seat in elevation. Fig. 3 is a cross section of such casing at the front 50 end thereof, showing the seat in end elevation in the lowered position ready for use. Fig. 4 is a perspective view showing the application of the invention to a seat made and operated as a single unit. Fig. 5 is a side ele-

vation showing the seat in the position for 55 use.

The same reference characters indicate the same parts in all the figures.

Referring first to Figs. 1, 2, and 3, 10 represents a toilet hopper or bowl. 11, 11 represent the seat members which are arranged at opposite sides of the bowl and are adapted to extend partially thereover when in position for use, leaving a space between their adjacent edges. In the position shown in 65 Figs. 1 and 2 these seat members are raised and at the same time are withdrawn beyond the rim of the bowl and out of the way. As both seat members are alike and the means for operating them are identical, I will describe only one, applying reference characters used in such description to corresponding parts of the other. The seat member is supported adjacent to one edge or limit, which is the inner edge when in position for 75 use and the lower edge when withdrawn, by pins or studs 12 at its front and rear ends, which are contained in slots 13 in plates 14, 14, between which this part of the seat member is contained. These plates, or arms, as 80 they may also be called, are pivoted on pivot pins 15 between lugs 16 on the top of the casing 17 at one side of the bowl. The two casings are supported in part by posts 18 and are rigidly connected by cross bars 19 85 and 20, the latter having a web adapted to rest on the rear part of the toilet bowl and the post being adapted to rest on the floor. These parts are thus united in a rigid frame work and have a three point support, and 90 being thereby independent of inequalities and variations in different installations. The front cross bar 19 is close to the bowl and nearly in the same vertical plane with the forward end of the seat, and therefore does 95 not interfere with the use of the toilet. The inner or swinging ends of the plates 14 are contained in slots in upstanding posts 21 of the crossbars, in which they are retained with capability for some up and down movement by pins 22 which pass through slots 23, the latter being concentric with the pivot 15, or approximately so. Each post 21 is internally recessed and contains a spring 24 which presses upwardly on the under edge 100 of the plate 14 and reacts against a plug 25 screwed into and closing the end of the recess or socket in the post. The outer edge of the

105

seat member is supported by endwise movable rods 26 which pass from the interior of the casing through the top thereof and are engaged with pins 27 carried by brackets 28 fixed to the seat near its outer edge. The rods have elongated eyes forming slots 29 which receive the pins 27 and give opportunity for lost motion for a purpose presently to be described. There are two rods 26 for each seat section, arranged adjacent the forward and rear ends thereof, respectively. Each rod is connected by the pivot 30 with a lever 31 pivoted at 32 within the casing near the opposite end thereof from its connection with the rod. The two levers 31 cross and are engaged at their intersecting point by a pin 33 to which there is also connected a link 34, the latter passing through the bottom of the casing and being pivoted at 35 to a treadle lever 36. This treadle lever passes across the front of the toilet below the seat and its ends are bent back under the two casings and pivoted in brackets 37 depending from the rear parts of these casings. The one treadle 20 is thus a part of two levers. Said pin 33 is fixed in one of the levers 31 and slides in a slot 38 in the other, which is provided to allow for the varying angularity of the levers. On each of the rods 26 is a spring 30 latch 39 adapted to engage under the end of a rigid projecting abutment 40 on the inner wall of the casing, this latch being provided to hold the seat in the horizontal position against the pressure of the spring 41, which 35 is connected with the pin 35 and with a stud 42 inside the casing, and constantly exerts force tending to raise the treadle, the link 34, levers 31, and the seat. Spring 40 is conveniently made of a single piece of spring 40 sheet metal and is provided with a projecting lug 43 at one side. The plate or arm 14 has a finger 44, which projects through the adjacent wall of the casing and extends to the lug 43. When the arm is in the position 45 shown in Fig. 3, said finger 44 does not interfere with the latch, but leaves the latch engaged with the abutment 40. The position illustrated in this figure is that taken as soon as the treadle is depressed. The seat has 50 then been brought into approximately horizontal position, the studs 12 traveling along the slots 13 in the arms 14, and the outer portions of the seat being held depressed by the latches 39. The arms 14 are held up by the 55 springs 24. If now a weight is placed on the seat, such as is applied when a person sits on it, the inner part of the seat is depressed, lowering the arms 14 and pushing the fingers 44 outwardly, that is, to the right with respect to Fig. 3. It should be observed that these fingers are below the pivots 15 so that depression of the arms moves the fingers horizontally. In such movement the finger 60 engages the lug 43 of the latch 39, disengaging said latch from the abutment 40 and

leaving the rod 26 free to rise. The lost motion between the rod and the seat, permitted by the slot 29, allows the rod to be raised by spring 41 far enough to lift the latch clear of the abutment 40, whereupon only the 70 weight of the occupant retains the seat in the horizontal position. Now as soon as this weight is removed, the spring 41 is left free to raise the seat and in so doing it raises the outer part of the seat and causes the inner 75 part to travel along the slots 13, being thereby withdrawn from the position over the hopper. I prefer to extend the brackets 28 far enough to bear on the top of the casing 80 17 when the seat is lowered, or to provide an equivalent device for the same purpose, this purpose being to prevent depression of the outer part of the seat under the weight of the occupant far enough to take up the lost motion of the rod 26. It is apparent that if the outer part of the seat were permitted to descend far enough to take up this lost motion, the rod would not be raised when the latch 39 is disengaged, and the seat might 85 not be released when the weight is removed 90 from it. The provision of a support for the outer limit of the seat, either by the bracket 28 or other means, prevents such a result.

The mechanism shown in Fig. 4 is essentially the same in character. Here the seat 95 111 is movable as a unit and is arranged so that its rear end is raised and its forward end is caused to move back and forth in the path defined by the guiding slots 45 in arms 46 arranged at the opposite sides of the 100 toilet, the seat having studs 48 occupying such guide slots or guideways. The arms 46 are supported by posts 49 and 50, being pivoted to the forward post 49 by a pivot pin 51 and connected to the rear post by a pin 52 105 which passes through a slot 53 in the arm curved about the pivot 51 as a center. The treadle 54 is a bar passing across the front of the toilet having its ends bent to the rear and pivoted at 55 to the front posts 49, the 110 rear ends of the lever arms formed on such bar carrying studs 56 which occupy and slide in slots or guideways 57 in a three armed lever 58, which is pivoted to the post 50, by a pin 59. The second arm of this lever is 115 connected by a link 60 with the seat adjacent to the rear end thereof, the connection being essentially the same as that between the rod 26 and the seat shown in Fig. 3, that is having provisions for lost motion permitting a 120 limited upward movement of the link 60 when the latch is released and the seat remains in the horizontal position. The latch is shown at 391 and is essentially the same as the latch 39, being secured at one end to the 125 link 60 and having a lug 431 at one side. The latch coöperates with an abutment 61 which is formed on one end of a bar 62 secured to the posts 49 and 50, such end terminating in the path of the latch, and being 130

beveled on its upper side, whereby the latch will pass over it and be deflected, so that it may spring out under the abutment after passing the same. The arm 46 has a finger 63 projecting adjacent to the position occupied by the lug 431 when the latch is engaged with the abutment as described. This finger and the lug 431 are relatively so shaped and arranged that the finger, when 10 depressed, exerts a wedging action thereon, disengaging the latch from the abutment. A spring 64 is connected to the arm 65 of the three armed lever 58 and also to an arm 66 fixed to and projecting from the arm 46. 15 The spring is under such tension that it exerts a pull between the arms 65 and 66, tending to raise the link 60, raise the treadle 54, and raise the rear end of arm 46, that is, its function is to hold the parts in the position shown in Fig. 4, and to return the parts 20 to such position from any other position. It will be understood that when the treadle is pressed upon the pin 56 is raised and the lever 58 is oscillated, pulling down upon the 25 link 60, and bringing the seat into the position for use, the studs 48 then sliding along the guideways 45 until the forward end of the seat is approximately flush with the forward ends of the arms 46. When this position 30 has been reached the latch 391 has passed beyond and becomes interlocked with the abutment 61, and a pin or equivalent projection 67 on the rear part of the seat overlies the arm 46 in rear of the pivot there- 35 of. Now when a weight is placed upon the seat, the rear end thereof is depressed, depressing the rear end of arm 46, and causing the finger 63 to wipe across the lug 431, and by its cam action disengage the latch. The 40 spring 64, being under tension, immediately moves the lever 58 and link 60 until the lost motion between the link and the seat is taken up, thus causing the latch to be raised above the abutment. The seat being now 45 unlocked will rise and withdraw as soon as the weight of the occupant is removed therefrom.

It will be appreciated that in each form of the invention the surface of the seat which 50 is uppermost when in position for use is turned toward the toilet bowl when withdrawn, or in other words, is exposed toward the bowl. Thus any sheets of paper which may have been placed on the seat as a sanitary covering are caused to slip off automatically in the bowl and are disposed of without effort or care on the part of the user, and also in a manner which causes them to be finally disposed of and not fall upon the 55 floor and cause an obnoxious litter.

Comparing the two illustrated embodiments of the invention it is apparent that they are alike in all essentials. In each the outer limit of the seat is raised and lowered 60 in operation, while the inner limit thereof is

at the same time correspondingly withdrawn and advanced. In this use of the terms "inner" and "outer," I define as the outer limit of each form of the seat, that edge or end thereof which is more remote from the 70 toilet bowl when withdrawn, the inner limit or end being, of course, the opposite edge or end of the seat. It is of course understood that I do not limit the invention to the exact arrangement of parts and operating mechanism here shown, nor do I limit the location of the seat or seat members to any particular side of the toilet bowl nor the directions of movement thereof to any specific directions. The important thing is that when withdrawn 80 the supporting surface or operative surface of the seat is the one which is turned toward the bowl, so that anything which may have been placed upon it may be discharged by gravity into the bowl.

What I claim and desire to secure by Letters Patent is:

1. The combination with a toilet bowl of a seat adapted to be placed over and withdrawn from said bowl, and means for causing said seat when withdrawn to expose the seating surface thereof toward the bowl and at an inclination thereto.

2. A water closet seat, means for operating said seat to raise and lower the same, and means for so guiding the seat as to cause its surface which is uppermost when the seat is lowered to be turned toward the closet when the seat is raised.

3. The combination with a toilet, of a seat, means for supporting the inner portion of said seat in a manner causing it to slide back and forth in a definite path, and means for raising and lowering the outer portion of said seat, whereby the seat when raised and withdrawn is caused to expose the operative surface thereof.

4. A rigid seat for water closets adapted to be advanced into operative position and withdrawn into inoperative position, and means for guiding the opposite limits of said seat in respectively different directions, whereby in being thus withdrawn the seating surface of the seat is exposed.

5. A seat for water closets adapted to be advanced into operative position and withdrawn into inoperative position, and means for guiding the inner portion of said seat in a backward and forward direction and the outer portion thereof upwardly and downwardly above the operative position of the seat, whereby when withdrawn the seating surface of the seat is in exposed position.

6. The combination with a seat, of substantially horizontal guiding means with which the inner part of the seat is movably engaged, and means for raising and lowering the outer portion of the seat, whereby when said portion is thus raised the inner portion is retracted, and vice versa.

7. The combination of a seat, means for raising and lowering the outer limit of such seat, means for constraining the inner limit of the seat to travel back and forth when the outer limit is thus raised and lowered, a latch for holding the raising and lowering means in its depressed position, means operable when a weight is placed on the seat for disengaging said latch, and a constantly acting means tending to raise the seat.

8. In combination with a seat, upwardly and downwardly reciprocating means connected with the outer portion of said seat for raising and lowering the same, a yieldable support for another portion of the seat, a latch connected with said means operative to lock the same in its depressed position, and means whereby said support is caused to disable said latch when a weight is placed upon the seat.

9. The combination of a seat, a pivoted arm having a substantially horizontal guideway with which one portion of said seat is slidingly engaged, a spring tending to raise said arm, means for raising and lowering another part of said seat, a latch adapted to become operative when said raising and lowering means is in the lowered position to retain the same in such position, and a finger projecting from said arm in such relation to the latch as to disable the same when said arm is moved by a weight placed upon the seat.

10. The combination of a seat, a pivoted arm having a substantially horizontal guideway with which one portion of said seat is slidingly engaged, a spring tending to raise said arm, means for raising and lowering another part of said seat, a latch adapted to hold said raising and lowering means in the lowered position, and a finger projecting from said arm in such relation to the latch as to disengage the same when said arm is moved by a weight placed upon the seat, said raising and lowering means having a lost motion connection with the seat and being under a resilient pressure tending to raise it, whereby it is automatically removed from locking position upon disengagement of said latch.

11. The combination with a toilet bowl of a rigid frame having a three point support, two of such points being on the floor at opposite sides of the bowl and the third being on the bowl itself, and a seat supported on said frame in a manner permitting projection of the seat over the bowl and retraction.

12. The combination with a toilet bowl of a rigid frame structure arranged with parts at opposite sides of the bowl and a connecting portion crossing a part of the bowl, seat members mounted upon the frame structure at opposite sides of the median plane of the bowl, and supporting elements as-

sociated with said frame structure arranged in position to bear upon the bowl and upon the floor adjacent to said bowl, respectively, said supporting elements being three in number and arranged out of a straight line, whereby to afford a stable three-point support for the frame and seat members.

13. The combination with a toilet bowl of a frame structure comprising portions located at respectively opposite sides of the bowl and a connecting member extending from one of said portions to the other across a part of the bowl, a supporting element connected to said connecting member and bearing on the bowl, a supporting element connected with each of the aforesaid portions of the frame structure and arranged to rest on the floor, and a seat member mounted upon each of said portions.

14. The combination with a toilet bowl of two casings and connecting bars rigidly secured to said casings and forming therewith a rigid frame structure, a seat member pivoted on each of said casings, the casings being spaced apart to occupy positions at opposite sides of the bowl and to hold said seat members at opposite sides of the middle part of the bowl, and one of said connecting bars crossing the rear part of the bowl and having a supporting element resting thereon, and posts connected to the casings adapted to bear on the floor at each side of the toilet.

15. The combination with a toilet of a frame including a bar crossing the rear part of the toilet and having a support thereon and posts at each side of the forward part of the toilet adapted to rest on the floor, guiding means carried by said frame at opposite sides of the toilet, seat members slidingly engaged at their inner portions with said guiding means and mechanism for raising and lowering the outer portions of said seat members.

16. In combination with a water closet, a seat, means connected with the outer limit of said seat and operable to raise and lower the same, a substantially horizontal guide for the inner limit of the seat, said guide being movable against yielding resistance under a weight placed on the seat, a displaceable latch for holding the raising and lowering means in lowered position, and means operable by depression of said guide for disabling said latch.

17. In combination with a water closet, a seat adapted to be placed thereover, a substantially vertical rod connected to the outer portion of said seat with provision for lost motion vertically, said rod being movable up and down, a spring acting on said rod with tendency to raise the same, a treadle connected with the rod and operable to depress the same against the pressure of said spring, a substantially horizontal guide with

which the inner portion of the seat is engaged and by which said portion is constrained to move back and forth when the outer part of the seat is raised and lowered, 5 said guide being movable downwardly against resilient resistance under pressure of an imposed weight, a spring latch carried by said rod, an abutment arranged to be engaged by the latch when the rod is in the de-

pressed position, and means for disengaging the latch constructed and arranged to be operated by the said guide when moved by a weight, the lost motion between the rod and seat enabling said latch to be raised clear of the abutment. 10

In testimony whereof I have affixed my signature.

WARREN C. REES.
